UNITED STATES PATENT OFFICE

GREGORY N. EBEL, OF ST. PAUL, MINNESOTA

CHICKEN-FEEDING HOPPER

Application filed May 3, 1929. Serial No. 360,254.

This invention relates to stock feeders and especially to a poultry feeding device.

An object of this invention is to provide a poultry feeder of minimum cost and to so construct the parts that a single part performs multiple functions and at the same time to provide a feeder in which there is a minimum waste of food and especially to provide against the loss of food by the tendency of fowls to "hoe" the food with the bill and also to prevent the fowls from contaminating the food with droppings and generally to provide a device of this character which not only saves in both the labor and material of construction but also saves in the labor and material in the feeding of the poultry and in the cleaning and care of the device.

With the above and other objects in view, I have invented the device illustrated in the accompanying drawings, in which:

Figure 1 is a front elevation of my device.

Figure 2 is a section at 2—2 Figure 1.

Figure 3 is like Figure 2 but with the sliding door 9 in an elevated position.

Figure 4 is a side elevation with the cover removed and used as a tray.

Like reference characters indicate like parts throughout the following specification and in the drawings, in which 1 indicates a cover member performing a triple function of covering and providing a slip incline and also providing a tray. The slip incline is for the purpose of preventing fowls from roosting on the cover and thereby amongst other things preventing them from fouling the food by droppings. The cover 1 is at an incline of substantially thirty degrees to the horizontal and sufficient so that the feet of the fowls will slip thereon so that it cannot become a resting or roosting place. The cover 1 is carried by side walls 15 and a back wall 16 and is flanged on three sides, the flanges 14 fitting outside the walls 15 and the flange 13 serving as a hook to prevent the cover from gravitating or sliding from its seat. When the cover is removed and inverted as shown in Figure 4 it serves as a tray for withdrawing the savings from the bottom of the feeder. Below the cover 1 is an in-

clined wall or bottom 2 at the lower end of which and a continuation of which is a vertical septum 3 and another inclined bottom 6 is inclined opposite to bottom 2. At the lower end of wall 6 is an upwardly extending stop wall 7. Below the wall 6 is a saving chamber 4. Substantially the entire front is formed by a sliding door 9, which when in its lowermost position as shown in Figure 2 serves as a front closure for chamber 4 and when in its uppermost position serves as a closure for the feeding chamber as shown in Figure 3 and is held upward by a latch 8, the latch 8 being duplicated on the opposite side and the two latch members being pivotally mounted to the walls 15. Between the wall 7 and door 9 is an open space 16' or neck leading to the chamber 4. In vertical alignment with the wall 3 and extending upward to the cover 1 is a sliding and removable wall 5. When food is poured into the top it strikes against the walls 16 and 2, and the door 5 when used, and gravitates until stopped by the wall 7 leaving, between the walls 7 and 3, a feeding space of sufficient size to conveniently accommodate the neck and head of the fowl. The tendency of the fowl is to "hoe" the food with the bill for the purpose of selecting the better particles of food and this hoeing of the food is the occasion of great waste in poultry feeding. By the arrangement herein, the wall 7 retards the food from being thrown out by this hoeing process and the neck 16 catches any food that is drawn over the wall 7 and preserves it in the chamber 4. The cover 1 must first be placed under the hopper and then by the lifting of the door 9 the hopper may be emptied into the top 1 and held in the top 1 by the end flange 13, together with the side flanges 14, and then by reversing the top 1 the food may be poured from the end opposite the flanges 13 into the hopper and again used or may be poured into any suitable receptacle and carried away. Since the flanges 13 fit over the sides at both the top and bottom, it will be seen that the emptying of the chamber 4 into the cover 1 is without waste as owing to this fit there is no side escapement over the walls 14 nor between the walls 14 and the 100

body nor backward as the body serves as a back wall for the tray during the emptying process. When used as a cover, the member 1 extends in the form of an eves or protecting 5 brow over and beyond the wall 7 and even covers the neck of the chamber 4 so that it is impossible for droppings from the fowl to contaminate the food even though the fowl is enabled to maintain itself on the cover 1 for a moment, and furthermore when the 10 fowl jumps, these droppings are a common occurrence; as in such jumping especially to the top of the feeder heretofore no provision has been successfully had to prevent the incident contamination of the food, while the 15 hopper is open for use.

When it is desired to close the feed trough, the door 9 is elevated to the position shown in Figure 3 and the latch 8 turned thereunder 20 so that it serves the dual function of closing both the chamber 4 and the food trough selective at will.

The door 5 is for the purpose of regulating the feed when coarser or very bulky millfeeds 25 or grains are used, and may when not in use be stored in the chamber 4.

Behind the latches 8 are bumpers 17 adapted to prevent the movements of the latch beyond a predetermined position.

Beneath the top of the wall 2 and in vertical alignment with the door 9 is a cleat 12, which serves the dual function of reinforcing and also serves as a handle whereby the device may be carried in one hand as by the bail 30 of a bucket. At the rear are a pair of cleats 10 and 11, the cleat 10 being provided with a pair of keyhole slots 18 for the purpose of hanging the device upon the wall and in which event, especially since almost all coop 35 walls are damp at certain times, the cleats space the feeder from the wall sufficiently so that no trouble is had with the food becoming mouldy or musty by reason of becoming damp from the walls, and provide a free circulation of air between the walls and feeder and prevent a direct contact of the hopper with the wall. These cleats also serve as a reinforcement.

The wall 7 is provided with a ridge 20 to 50 aid in preventing the hoeing out of the feed into the saving chamber 4.

While this feeding device is suitable for grain which will work very nicely in this hopper, it is especially adapted for the feeding 55 of mash or millfeeds. When the door 5 is inserted, it is intended that the coarser or very bulky millfeeds or grain be fed through the neck forward of the door, which restricts the hopper area.

60 Claims:

1. In a poultry feeding device, a box provided with a vertical side wall, a hopper within the box, the base of the hopper depending within the box at an acute angle to the side wall and terminating in an upwardly extend-

ing portion at substantially right angles to the depending portion, and a septum within the box forming a side wall of the hopper and extending vertically above the depending portion and spaced apart from the depending portion to form a feeding neck, the hopper provided with an incline extending from the said upwardly extending portion and a sliding septum in alignment with the said vertical septum. 70

2. In a poultry feeding device, a box having a horizontal base, vertical walls extending upward from the base, a cover member at an acute angle to the rear wall and at an obtuse angle to the front wall, a septum within the box depending from the cover member, a portion of the septum slidably detachable, a hopper, the septum forming one wall for the hopper, a base for the hopper, inclined at an acute angle to the rear wall and provided with an upwardly extending terminal beyond the septum. 80

3. In a chicken feeder a hopper provided with a tortuous path, and a top so constructed as to form a scoop to receive otherwise wasted feed from said hopper, said tortuous path including a relatively short terminal wall and a strip breaking the continuity of the surface of said wall, said wall being inclined, said feeder having a window opening exposing said path, a closure for said opening, said top forming a closure for said hopper, said last closure having three side walls and an open end whereby it may be fitted under said feeder to receive the contents of the feeder which may be withdrawn therefrom which would otherwise have been wasted. 90

4. A device as described including a box, a hopper formed therein, a trough directly under the hopper, a chamber under the trough, a closure for the chamber, said closure forming a deflector to direct feed overflowing from the trough into chamber, and a closure for said box inclined at an angle to prevent roosting thereon. 100

In testimony whereof I affix my signature.
